UNITED STATES PATENT OFFICE.

ALBERT W. P. VERGEER, OF NEW YORK, N. Y., ASSIGNOR TO THE T. F. MOORE COMPANY, INC., OF NEW YORK, N. Y., A CORPORATION OF NEW YORK.

DISPLAY DEVICE.

Application filed July 6, 1925. Serial No. 41,482.

This invention relates to collapsible display devices, and more particularly to such devices for advertising goods sold in containers. The invention aims to provide a display device of simple and cheap construction which may be readily opened or set up and folded or collapsed, and which when set up will present, in addition to other advertising or display matter, an attractive replica of a container of the goods to be displayed.

For display purposes it has been customary, heretofore, to mount containers such as those of canned goods, in recesses provided in display cards. Such arrangements have proved unsatisfactory in that the display must necessarily be dismantled for transporting it from place to place, and also in that if dummy containers or the actual goods to be displayed are packed with the other parts of the display a considerable amount of space is required.

In accordance with the present invention, instead of mounting an actual container in the recess of a display card, a flexible sheet or member bearing the label of the goods for which the device is to be used is attached to the card and protrudes through the recess in such a manner that it is for display purposes made to assume a shape corresponding to that of a container, or can be flattened out to lie approximately parallel to the card for transportation.

An understanding of the invention can best be given by a detailed description of a device embodying the same, and such a description will now be given in connection with the accompanying drawings showing such a device which embodies the features of the invention in the form now considered best. In said drawings:—

Fig. 1 is a front elevation of the device in display position;

Fig. 2 is a sectional view of the device in display position taken on the line 2—2 of Fig. 1;

Fig. 3 is a sectional view of the device in display position taken on the line 3—3 of Fig. 1;

Fig. 4 is a back elevation of the device in folded position; and

Fig. 5 is a sectional view of the device in folded position taken on the line 5—5 of Fig. 4.

Referring to the drawings, the display device illustrated comprises a display card 10 constructed of some stiff sheet material, such as cardboard, on the front side of which display matter is printed or otherwise displayed. The card is provided with an opening or aperture 11, opposite edges of which are extended in such a manner as to form slots 12 and 13. Protruding through the opening 11 with opposite edges extending into the slots 12 and 13 is a member 14 constructed of flexible sheet material. The member 14 is so arranged that it may be made to protrude through the opening in the card in such a manner as to represent, or form the replica of, half of a cylindrical container, or may be flattened out to lie approximately parallel to the card. Such protrusion is limited by extensions 15 and 16 on the ends of the member 14, the extensions being adapted to engage the back of card 10.

One end of the member 14 is secured to the card 10 by means providing a hinge connection at one edge of the opening 11. For this purpose in the device shown a locking tab 19 projects from one edge of the opening 11 and enters a slot 20 in the member 14. The tab 19 is formed with undercut ends which may be folded over to allow it to enter the slot 20 when assembling the device, after which it holds the member 14 hinged securely to the card both in set-up and flattened-out position. A plain tab 18 projecting from the opposite edge of the opening 11 is adapted to enter a slot 17 in the free end of the member 14 when the member is in set-up position to hold it in that position.

To complete the configuration of half a container, the side wall of which is formed by the flexible member 14, two semi-circular flaps 21 and 22 are provided projecting from opposite edges of the opening 11 and adapted to be turned outwardly along the dotted lines 21^a and 22^a to form the top and bottom respectively of the configuration. When, as in the device shown, the member 14 is intended to take a half-cylindrical form, the flaps 21 and 22 will be of semi-circular shape.

For supporting the card 10 in display position, a folding prop 23 is hinged to the back of the card 10. The bottom edge of the prop will extend at a suitable angle to the hinge line to support the card at a desired inclination. For locking the prop

in its operative position, a locking flap 24 is provided hinged to the card 10 in position to turn outward in a recess 25 in the prop and having a slot 26 to engage the edge of the recess.

The prop 23 extends above the opening 11 and is hinge-connected to the card 10 above and below the opening, and it has opposite the opening 11 a projecting portion 23^a which extends beyond the hinge line of the prop so that when the prop is turned outward from the card 10 to its operative position, this extension 23^a will be turned to project through the opening 11. In so turning to project through the opening 11, the extension 23^a will force the flaps 21 and 22 outward within the forwardly bulging member 14 to about the positions shown in Fig. 2. If the extension 23^a were made 20 of a length sufficient to turn the flaps outward to positions at exact right angles to the card 10, it would not, in being turned through the opening 11, exert pressure on the flaps at a sufficient distance from the 25 fold lines of the flaps to force them outward. The extension is therefore made of a slightly less length so as to press on the flaps 21 and 22 at points slightly removed from their fold lines. The extension thus 30 forces the flaps outward to position in which they stand nearly but not quite at right angles to the card 10. If desired, the flaps may be readily pushed into position at exactly right angles to the card by hand. 35 Assuming the device to be in folded position, that is, with its component parts lying approximately parallel to the card 10, as shown in Figs. 4 and 5, the device may be set up for display purposes as follows:— 40 The flexible member 14 is first urged through the opening 11 of the card to bulge outwardly in approximately the shape of a half cylinder, and the slot 17 in the free end of the member is slipped over the tab 45 18 to hold the member in this position. The prop 23 is then turned to extend at right angles to the card, and as it turns its extension 23^a turns forwardly through the opening 11 and forces the flaps 21 and 22 outward into the forwardly bulging member 50 14 to insure the desired form thereof and to provide the ends of the replica of the ar-

ticile to be displayed. The prop is locked in position by the locking member 24.

When it is desired to store or transport the device the locking member 24 and prop 23 are folded flat against the card 10, and the flaps 21 and 22 are pushed inward, and the end of the member 14 is then disengaged from the tab 18 and flattened out so that part of it lies approximately parallel to the back of the card and part approximately parallel to the front of the card as shown in Figs. 4 and 5. In this condition the device requires but a small amount of space either for transporting or storing.

It is to be understood that the invention is not to be limited to the exact construction and arrangement shown, but that it includes changes and modifications thereof within the claims.

What I claim is:

1. A collapsible display device, comprising a display card having an opening therein, a sheet of material adapted to be bent and to protrude through said opening to represent a part of a container, means for holding said sheet in set-up position, flaps extending from opposite edges of said opening and adapted to be turned forward within said bent sheet, and a folding prop hinged to the back of said card and having a part projecting beyond its hinge line adapted to turn said flaps outwardly when the prop is turned to set-up position. 85

2. A collapsible display device, comprising a display card having an opening therein, a flexible member protruding through said opening in the shape of a portion of a container and adapted to be flattened out to lie approximately parallel to said card, a plurality of flaps constituting in set-up position the ends of the configuration formed by said first-mentioned member and adapted to fold into a plane coincident with that of said card, and a prop hinged to the back of said card and adapted to fold into a plane parallel to that of the card and having an extension for holding said flaps in set-up position. 90 95 100

In testimony whereof I have hereunto set my hand.

ALBERT W. P. VERGEER.
